(57) **CLAIM**

The ornamental design for an air mattress with cover, as shown and described.

DESCRIPTION

2. Air mattress with cover

FIG. 2.1 is a top perspective view of an air mattress with cover showing our new design;

FIG. 2.2 is a first end perspective view thereof;

FIG. 2.3 is a second end perspective view thereof;

FIG. 2.4 is a right edge perspective view thereof;

FIG. 2.5 is left edge perspective view thereof;

FIG. 2.6 is a top plan view thereof; and

FIG. 2.7 is a bottom plan view thereof.
